UNITED STATES PATENT OFFICE.

WILLIAM ALLINSON, OF DES MOINES, IOWA.

DRIER.

Application filed July 30, 1924. Serial No. 729,097.

To all whom it may concern:

Be it known that I, WILLIAM ALLINSON, a citizen of the United States, and a resident of Des Moines, in the county of Polk and State of Iowa, have invented a certain new and useful Drier, of which the following is a specification.

The object of my invention is to provide a drier of the tumbler type used in laundries and other places.

More particularly, it is my object to provide a drier of the kind mentioned of simple, durable and inexpensive construction.

A further object is to provide such a drier having a reversible rotating drum or the like and means for supplying heated air thereto and drawing heated air therefrom, whereby the air passing the tumbler or rotating drum remains substantially at atmospheric pressure.

More particularly, in this connection, it is my purpose to provide in such a structure a tumbler arranged within a casing, means for forcing heated air into the casing, and means for drawing air from the casing.

A further object is to provide in such a machine means for regulating the flow of air, so as to permit air to be moved simultaneously through the tumbler casing from the atmosphere and from a heater and for regulating the relative amounts of heated and fresh air.

With these and other objects in view, my invention consists in the construction, arrangement and combination of the various parts of my drier, whereby the objects contemplated are attained, as hereinafter more fully set forth, pointed out in my claims, and illustrated in the accompanying drawings, in which:

Figure 1 shows a perspective view of a drier embodying my invention, parts being broken away.

Figure 2 shows a horizontal, sectional view through the fans or pumps.

Figure 3 shows a vertical, sectional view through the drier, taken from front to rear substantially at the middle of the drier; and

Figure 4 shows a perspective, detailed view, partly in section, illustrating one of the bearings or boxings for the tumbler shaft.

Generally speaking, my structure involves a compartment in which are mounted the 55 rotating drum or tumbler, a compartment for steam heating pipes or the like, and compartments for fans or pumps. The general arrangement is such that air may be forced by a fan through the heater compartment and thence through the tumbler compartment, and is also such that one or more of the fans may be used for pulling the air from the tumbler compartment.

In the accompanying drawings, I have 65 used the reference numeral 10 to indicate generally the side walls of the device. The side walls are connected at the rear of the device by a rear wall 11 and at the top and bottom by a top wall 12 and bottom wall 13 70 respectively.

At the front of the device, a wall 14 is inclined downwardly and forwardly from the top 12, as shown.

From the lower edge of the inclined wall 75 member 14, there extends downwardly a wall member 15 in which is a door 16.

From the lower edge of the wall portion 15, a casing or compartment member or wall 17 extends downwardly and rearwardly 80 to the bottom wall 13. The heater compartment and the tumbler compartment are separated by means of a connecting partition or wall 18, connecting the end walls 10 and inclined from its upper end near 85 the top of the device, but spaced from the top 12 downwardly and rearwardly as shown.

Another partition member 19 extends from the lower edge of the wall or partition 90 18 downwardly and forwardly to the bottom wall 12.

A horizontal partition or wall 20 extends from the partition 19, as shown in Figure 95 3, rearwardly to the rear wall 11 and extends from side to side in the machine.

It will thus be seen that there is provided by the walls 10, 12, 14, 15, 17, 18 and 19 a compartment A for the tumblers. There is provided by the walls 10, 11, 12, 18, 19, 100 20 a compartment B for the heating coils, and by the walls 10, 11, 13, 19 and 20 a compartment C for the fans.

The compartment C is divided into three sub-compartments by vertical partitions 21 105 and 22, such compartments being indicated

at C¹, C² and C³ in Figure 2, the latter compartments being those provided for the fans and fan casings.

A horizontal shaft 23 extends through the compartment C and the sub-compartments C¹, C² and C³, as shown in Figures 1, 2 and 3, projecting from the main casing and having on one of its outer ends a gearing device, such for instance as the pulley 24.

10 Mounted on the shaft 23 within the sub-compartment C¹, as shown in Figure 2, is a fan or pump device 25 received within a suitable casing 26, which has an opening 27 at the side and a passage 28 projecting 15 through the rear wall 11.

A similar pump or fan 25^a is mounted on the shaft 23 in the sub-compartment C³ in a similar casing 26^a. The casing 26^a is provided with a side opening 27^a and a rear outlet passage 28^a similar to the opening 27 and passage 28.

20 In the sub-compartment C², there is mounted on the shaft 23 a similar fan or pump 29 in a casing 30, having an intake opening 31 at its side and having a passage 32 extending upwardly through the partition 20 for the passage of air from the sub-compartment C² to the heater compartment B.

30 It will be noticed that the lower portion of the compartment A is tapered, as shown for instance in Figure 1.

Air is supplied through this lower part of the compartment A to the compartment C² 35 through a tubular passage 33 in the lower part of said compartment A, which passage 33 is not in communication with the compartment A, but is in communication with atmospheric air and the compartment C².

40 In the compartment B, I provide a suitable heating element, which may consist of the steam coils 34.

In the compartment A is a foraminous cage or tumbler 35 supported on a shaft 36 45 mounted in boxings or bearings 37, as shown in Figure 4, and having on one end outside the main casing a gearing device, such for instance as the pulley 38.

The tumbler 35 is preferably made of a 50 frame with screen wire or the like thereon and may be octagonal in cross section, as shown in Figure 3.

It has an ordinary door 39 for permitting access to its interior.

55 In the top 12 above the compartment A is an opening 40.

It will be noted that the wall 18 terminates at its upper edge below the top 12, thus leaving an opening or passage between 60 the compartments B and A.

Hingedly supported, as for instance on the top 12, is a closure member 41 adapted to be moved to a variety of positions, where it will close either the opening be-

tween the compartments B and A or the 65 opening 40 or neither of them.

A handle 42 is extended through the top 12 and is pivoted as at 43 just below said top. The handle 42 is connected by a link 44 with the closure member 41 as shown in 70 Figure 3.

For insuring further and more accurate and complete regulation of the movement of air through the tumbler compartment, there is provided in the passage 33 a hinged door 75 or closure member 45 supported on a rocking rod 46, which projects radially through one of the side walls 10 and has a handle 47 on its outer end.

Any suitable device 48 may be provided 80 for holding the handle 47 in different positions of its adjustment.

The lower tapered portion of the compartment A has openings 49 for providing communication between such compartment and the respective compartments C¹ and C³. (See Figures 1 and 2.)

In the wall 17 opposite each opening 49 is an opening 50, as shown for instance in Figure 1, for which there is provided a 90 sliding closure member 51, illustrated in Figures 1 and 3.

In the practical use of my improved drier, the clothes are put into the tumbler 35 through the doors 16 and 39. The fans are 95 operated from some suitable source of power, and the tumbler is rotated.

Ordinarily for the first part of the drying process, the closure members 51 are closed, the door 45 is opened, and the closure member 41 is moved to position for substantially closing the opening 40.

The central fan or pump 29 will draw air through the passage 33 and the opening 31 in the side of the fan casing, and discharge the air through the passage 32 forcing it through the compartment B, around the heating coils 34 through the opening between the partition 18 and the top 12 into the tumbler compartment A.

The fans or pumps 25 and 25^a cause suction in the lower part of the compartment A and draw the air through the openings 49 into the compartment C¹ and C³ and through the fan casings 26 and 26^a for discharging it through the passages 52, which may be connected with the outside of the building or otherwise, as may be desired.

My improved tumbler has a number of 115 advantageous features of construction forming desirable functions.

By using both blower and suction fans, I am enabled to maintain the air in the tumbler as nearly at atmospheric pressure as possible.

I find this desirable because it dries the clothes by contact with moving air, leaving the clothes in natural condition instead of

baking them as is done where a pressure pump only is employed.

By providing the suction fans and blower fan as herein shown and arranging the openings as shown, the circulation is easier to obtain and the circulation is made more uniform throughout the tumbler proper.

An important feature of this present invention lies in the peculiar arrangement whereby the device is made practically self-cleaning as to lint. Most tumblers are objectionable in that they collect lint on the interior of the tumbler casing, which gathers over the screens or barred openings employed and reduces the efficiency of the device to the extent that the openings are covered by lint. With my structure in which the lower part of the tumbler casing is tapered, as shown, and the openings are arranged, as disclosed in the drawings, we find that the lint is readily and easily drawn from the tumbler compartment, so that the device remains as efficient so far as lint is concerned at the end of the year as it is at the beginning.

The lint is simply drawn from the tumbler compartment and discharged at any suitable point.

There is an advantage in the octagonal cylinder here shown over a round cylinder in that the clothes are truly tumbled with a rather gentle movement instead of being dropped a considerable distance or beat. The buttons are not broken and the clothes are taken out in natural condition soft and loose.

Some changes may be made in the construction and arrangement of the various parts of my drier, without departing from the essential features and purposes of my invention, and it is my intention to cover by my claims, any modified forms of structure or use of mechanical equivalents, which may be reasonably included within their scope.

I claim as my invention:

45. 1. In a drier, a casing having a front tumbler compartment, a tumbler therein, a rear upper heater compartment, a heater therein communicating with the tumbler compartment, rear lower pump compartments 50 communicating with the tumbler compartment and the heater compartment respectively, pumps in said pump compartments, and means for regulating the action of the pumps for determining the pressure in the 55 tumbler compartment.

2. In a device of the class described, a tumbler compartment, a tumbler therein, a heater compartment communicating with the tumbler compartment, means for forcing air 60 through the heater compartment into the tumbler compartment, said tumbler compartment having a passage extending through but not communicating with the tumbler compartment for supplying air to said 65 means.

3. In a device of the class described, a tumbler compartment, a tumbler therein, a heater compartment communicating with the tumbler compartment, means for forcing air through the heater compartment into the 70 tumbler compartment, said tumbler compartment having a passage extending through but not communicating with the tumbler compartment for supplying air to said means, and means for drawing air from the 75 tumbler compartment.

4. In a device of the class described, a tumbler compartment, a tumbler therein, a heater compartment communicating with the tumbler compartment, means for forcing air through the heater compartment into the 80 tumbler compartment, said tumbler compartment having a passage extending through but not communicating with the tumbler compartment for supplying air to said 85 means, and means for drawing air from the tumbler compartment substantially across the tumbler compartment from the part thereof which communicates with the heater compartment.

5. In a device of the class described, a tumbler compartment, a tumbler therein, a heater compartment communicating with the tumbler compartment, means for forcing air through the heater compartment into the 90 tumbler compartment, said tumbler compartment having a passage extending through but not communicating with the tubular compartment for supplying air to said 95 means, and means for controlling the passage of air from the heater compartment to the tumbler compartment.

6. In a device of the class described, a tumbler compartment, a tumbler therein, a heater compartment communicating with the tumbler compartment, means for forcing air through the heater compartment into the 105 tumbler compartment and a passage extending through but not communicating with the tumbler compartment for supplying air to said 110 means, and means for closing said passage.

7. In a drier, a casing having a front tumbler compartment, a tumbler therein, a rear upper heater compartment, a heater therein 115 communicating with the tumbler compartment, rear lower pump compartments communicating with the tumbler compartment and the heater compartment respectively, pumps in said pump compartments.

8. In a device of the class described, a tumbler casing having a tapered bottom, a tumbler in said casing, means for forcing air into the upper portion of said casing, and means for drawing air from the lower tapered portion of the casing, whereby air is supplied to the tumbler at approximately 125 atmospheric pressure and lint is readily drawn from the tumbler casing.

9. In a device of the class described, a 130

tumbler compartment, a pump compartment divided by partitions into a plurality of separate compartments, a plurality of pumps mounted in said separate compartments on a single shaft, said pumps being arranged to respectively force air into the tumbler compartment and draw air therefrom.

10. In a device of the class described, a

tumbler compartment having a tapered bottom, a tumbler in said compartment, means for drawing air from the lower part of said tapered compartment at a plurality of points.

Des Moines, Iowa, June 11, 1924.

WILLIAM ALLINSON.
